Patented Nov. 21, 1922.

2 SHEETS—SHEET 2.

UNITED STATES PATENT OFFICE.

ARTHUR DUNBAR MARCOTTE, OF MEMPHIS, TENNESSEE.

BURGLAR ALARM.

Application filed June 3, 1921. Serial No. 474,708.

To all whom it may concern:

Be it known that I, ARTHUR D. MARCOTTE, a citizen of the United States, and a resident of Memphis, in the county of Shelby and 5 State of Tennessee, have invented certain new and useful Improvements in Burglar Alarms, of which the following is a specification.

This invention relates to a burglar alarm. 10 The object of the invention is to provide a device which may be mounted on any window or door of a building and adapted to cause an explosion when an intruder attempts to open the door or window.

15 It is also an object of the invention that the device be simple in construction and positive in operation.

It is a further object of the invention that the device is adapted to be quickly applied to 20 a window or door.

Other objects and objects relating to details of construction, combination and arrangement of parts will hereinafter appear in the detailed description to follow.

25 The invention is illustrated by way of example in the accompanying drawings, in which:—

Figure 1 is a detail elevation illustrating the use of the present invention when associated with a door.

Figure 2 is a front elevation of the device,

Figure 3 is a vertical central sectional view of the same.

Figure 4 is a top view of a modified form 35 of the device showing the same used in connection with a door, a portion of the door and casing therefor being shown in cross section.

Figure 5 is a front elevation of the same.

40 Figure 6 is a grouped perspective of the supporting frame elements.

Figure 7 is a perspective view of a tripper element which is employed when the device is used in connection with a window.

45 Referring to the drawings in detail, and particularly to Figures 1 to 3 inclusive, 10 indicates a base plate with which there is formed a pair of extensions 11 and 12, one near each end thereof, as shown. The lower 50 extension 12 is formed with an opening suitable for accommodating a cartridge receiv-

ing barrel 13, said barrel being of suitable dimensions to receive a 32 caliber cartridge as indicated at 14. The extension 11 is also provided with an opening suitable for receiving the tubular member 15, said member having a collar 16 formed on its one end and threaded upon its other end suitable for receiving the interiorly threaded end of the cylindrical casing 16. The upper end of the 60 cylindrical casing is formed with a closure as at 17 and through said closure there is provided an opening adapted to slidably accommodate the stem 18. The stem 18 extends through the tubular member 15 and 65 carries upon its lower end a firing pin 19. Intermediate the ends of the stem 18 there is formed a collar 20, and between the end 17 of the cylindrical casing 16 and collar 20, there is interposed a coil spring 21 adapted 70 to force the stem 18 downwardly; also the upper end of the stem 18 is threaded for receiving a knurled nut 22 as shown.

The extensions 11 and 12 are also provided with registering openings, which are adapted to receive a pin 22 as indicated in dotted lines in Figure 2. Upon this pin there is journaled or pivoted a trip lever 23, said lever having an enlarged end portion 24 through which the pin 22 extends and having its forward portion 25 bent at substantially right angles to its rear portion as at 26, so that the upper edge of the forward portion 25 when the trip lever is in the position shown in Figure 2, may engage beneath the lower end of the stem 18 and hold the same in its raised position, as shown in Figure 3, against the tension of the spring 21; also there is inserted between the enlarged or pivoted end 24 of the trip lever 90 and the extension 12 a tubular member as indicated at 26', the pin 22 passing therethrough as shown in dotted lines. The base 10 is formed with suitable openings at each of its ends adapted to receive the wood screws as indicated at 27, by which the base may be secured to a window casing or door casing with which it is intended to associate the device.

Referring to Figure 1, 27 indicates a door 100 and 28 the door casing. In this instance the device is secured to the casing 28 by means

of the screws 27 as shown. The stem 18 is raised to the position shown in Figure 3 and the trip lever 23 is swung to its position for supporting the stem 18 in this 5 raised position. When the tripping lever 23 is disposed in this position a part thereof extends in front of the door 27. A cartridge 14 is now placed in the cartridge barrel 13 and the alarm is set. In case a person 10 should attempt to open the door 27, as shown in Figure 1, the action of the door swinging inwardly would swing the lever 24 upon its pivot in an inward direction which would cause the same to free the stem 18 15 and permit the stem to descend under the force of the coil spring 21. The firing pin 19 will of course fire the cartridge 14 and the explosion caused would sound an alarm that someone was attempting to enter the 20 door.

Referring to Figures 4 to 6 inclusive the support for the device in this instance comprises the U-shaped member 30, which has secured thereto the L-shaped member 31, 25 by the means of rivets as indicated at 32. The upper leg 33 of the U-shaped member and likewise the free portion 34 of the L-shaped member are each provided with an opening 35, said openings being in vertical 30 alignment and adapted to slidably receive a stem 36. Intermediate the ends of the pin 36 there is positioned a transverse pin 37, which may taper toward its one end so that the same may be secured against removal. Between the pin 37 and the upper leg 33 of the U-shaped member there is interposed a coil spring 38 which is adapted to force the stem 36 downwardly; also the stem has threaded at its upper end a knurled 40 nut 39, by which it may be raised against the tension of the spring 38. The lower end of the stem 36 is formed with a centrally disposed firing pin indicated at 40, Figure 5, and upon the free portion 34 of the L-shaped member 31 there is pivoted a trip 45 lever 41 by the means of the bolt indicated at 42. The trip lever 41 is substantially the same shape as the trip lever 23 shown in Figure 2 and adapted to serve the same purpose with respect to holding the stem 36 in raised position as shown in Figure 5. In the lower leg 43 of the U-shaped member 30 there is formed a central opening 44 which is adapted to receive a cartridge barrel 13 shown in Figures 2 and 3. In this instance, however, upon the cartridge barrel there is threaded a knurled nut 46 so that the same may be held against removal. The bridge portion of the U-shaped member 30 is provided with a pair of openings 47, near each of its ends the upper pair of openings passing through the adjacent portion of the L-shaped member 31 and said openings being adapted to receive the wood

screws 48 by which the device may be secured to the door or window casing.

Also there is provided an L-shaped member 49 which is adapted to be positioned between the free portion 34 of the L-shaped member 31 and the lower leg 43 of the U-shaped member 30, as shown in Figure 3. The member 49 is provided with an opening 50 adapted to receive the threaded portion of the thumb screw 51, and likewise the bridge portion of the U-shaped member 30 is provided with an aligned threaded opening 52 into which the thumb screw 51 may be extended and thereby secure the member 49 to the U-shaped member 30. The free portion of the member 49 has formed therewith a pair of pointed pins 53, the purpose of which will later be explained.

Referring to Figure 4 it will be seen that the pins 53 of the member 49 are pressed into the casing of a door, thus affording 85 means for quickly attaching or securing the device in position, also as shown in Figure 5 the screws 48 are utilized for further securing the device in position. Screws may also be extended through the openings 47 in the lower end portion of the U-shaped member 31 if so desired and driven into the casing of the door, however, in such case the member 49 would not be necessary. It will be observed that the device, in this instance 90 should be secured a considerable further distance from the edge of the door than as shown in Figure 1. Also in this instance, there is an extension 54 pivoted to the trip lever 41 which is adapted to have its free end 95 disposed over the key hole 55 of the door as shown in Figure 5. The pivoted end of the member 54 is formed with a channel portion 56 which is adapted to receive the outer end of the trip lever 41 and is further adapted that when the arm 54 is moved in a direction away from the door to correspondingly move the trip lever 41; also it is adapted to be swung to a vertical position as shown in dotted lines in Figure 5.

The door knob spindle 57, in this instance, is provided with a downwardly depending arm 58, which has formed on its lower end an inwardly projecting portion 59 upon which the extension member 54 is adapted to rest.

With respect to the modified form of the present invention as shown in Figures 4 to 6 inclusive, it may be here mentioned that the same is particularly adapted for use when the person intends to leave the house and to set the device after passing through the door with which it is associated. In operating the device the stem 36 is first raised and the trip lever swung in position for supporting the same, a cartridge is then placed in the cartridge barrel 45 and the extension member 54 raised to its dotted line position as shown in Figure 5. A person may then

pass through the door and before entirely closing extend his hand between the door and casing and move the extension member 54 to its horizontal position as shown in Figures 5 4 and 5. Also before leaving the room a plug may be inserted in the key hole as indicated at 60, said plug being tapered toward its one end and only adapted to be removed when pushed inwardly, or in other words, 10 toward the extension member 54. The person may now close the door and the device is set. In case anyone would attempt to unlock the door by the use of the skeleton key, the plug 60 would be pushed against the end 15 of the extension member 54 and thus move the trip lever 41 inwardly sufficient for releasing the stem 36 and firing the cartridge within the cartridge barrel 45. When the person who had set the lock returns he may give the 20 door knob a quick turn and thus throw the extension member 54 to its position indicated in dotted lines in Figure 5, and then open the door for entering the room.

Referring to Figure 7 there is shown a 25 base plate 61 from one side of which there extends a substantially triangular shaped member 62. The member 62 is preferably made of wire as shown, and from the other face of the base member 61 there extends a 30 pair of points 63, one near each end thereof as shown. Also the base plate 61 is formed with a pair of openings 64, one near each end thereof. The purpose of the member just described is for use when the alarm device 35 is associated with a window, the device may be positioned as in Figure 1 upon the casing of a window and then the member shown in Figure 7 positioned upon the window sash so that when the sash is raised the triangular 40 portion of the triangular member 62 will engage with the trip lever 41 and move the same outwardly for releasing the pin 36. The downward stroke of the stem 36 will of course fire the cartridge and cause an explosion 45 as has been previously described.

I claim:

1. A burglar alarm of the character described, comprising in combination, a door, a cartridge firing mechanism, means for supporting said mechanism to the casing of said door, and means extending between said firing mechanism and the key-hole of the door whereby with the attempted unlocking of the door with a key said firing mechanism will be actuated.

2. A burglar alarm of the character described, comprising in combination, a door, a cartridge firing mechanism, means for securing said mechanism to the casing of said door adjacent the free end of the door, and means between the keyhole of the door and firing mechanism whereby upon the attempted unlocking of the door with a key said firing mechanism will be actuated for 65 firing the cartridge.

3. A burglar alarm of the character described, comprising in combination, a door, a cartridge firing mechanism, means for supporting said cartridge firing mechanism to the casing of said door adjacent the free end of the door, means between the keyhole of the door and firing mechanism whereby upon the attempted unlocking of the door with a key said firing mechanism will be actuated for 70 firing a cartridge, and means whereby the door may be opened from the exterior without actuating said cartridge firing mechanism.

4. A burglar alarm of the character described, comprising in combination, a door, a cartridge firing mechanism, means for supporting said firing mechanism to the casing of said door adjacent the free end of the door, a trip lever associated with said firing mechanism adapted to release the same when moved in a predetermined direction, and means extending between said trip lever and keyhole of the door whereby upon the attempted opening of said door with a key, 90 said trip lever will be moved for releasing said firing mechanism.

5. A burglar alarm of the character described, comprising in combination, a door, a cartridge firing mechanism, means for supporting said cartridge firing mechanism upon the casing of said door adjacent the free end of the door, a trip lever associated with said firing mechanism adapted to release the same when moved in a predetermined direction, a hinged extension for said trip lever adapted to have its outer end disposed when extended over the keyhole of the door, and means in said keyhole whereby on the attempted unlocking of the door with a 100 key the trip lever will be moved for releasing the firing mechanism.

6. A burglar alarm of the character described, comprising in combination, a door, a cartridge firing mechanism, means for supporting said cartridge firing mechanism upon the casing of said door adjacent the free end of the door, a trip lever associated with said firing mechanism adapted to release the same when moved in a predetermined direction, a 110 hinged extension for said trip lever adapted to have its outer end disposed when extended over the keyhole of the door, means in said keyhole whereby upon the attempted unlocking of the door with a key the trip lever will 115 be moved for releasing the firing mechanism, and means carried by the handle of the door whereby with the turning movement thereof the hinged portion of the trip lever may be drawn upwardly and permit the 120 opening of said door without moving said trip lever.

7. In a device of the character described, a plate, a pair of spaced lugs extending from the one face of said plate and arranged in 130

parallel relation with each other, means carried by one of said lugs adapted to support a cartridge, a spring pressed stem carried by the other lug and in alignment with the cartridge supporting means, a firing pin carried by said stem, and an elongated trigger bar having its one end terminating in a curved portion, said end being pivoted between the

lugs at a point adjacent one longitudinal edge of the plate whereby when the trigger bar is swung inwardly the curved portion thereof may be brought to engage beneath the associated end of the stem and the remainder portion thereof extend at substantially right angles to the plate. 10

ARTHUR DUNBAR MARCOTTE.
